Telephone & Telegraph Company, Chicago, Ill.,
a corporation of Delaware

Application April 2, 1937, Serial No. 134,500
In Great Britain April 3, 1936

10 Claims. (CL. 179—9)

The present invention relates to telephone systems and is more particularly concerned with systems having a plurality of interconnected exchanges such as for instance a main exchange associated with a number of satellite exchanges.

With such systems it is usual to employ at the satellite exchange an automatic switch which discriminates between local and outgoing calls and sets up a local call after absorption of one or more digits while possibly serving only as an impulse repeater for outgoing calls. Such a switch is known as a discriminating selector repeater.

It is the main object of the present invention to provide improved arrangements for route discrimination, digit absorption, zone metering and barred access control and which are so constructed that one portion may be capable of functioning without alteration in other systems for instance in a system employing register controllers. The improved arrangements can be simply adapted for use in satellite exchange networks of varying complexity and thus produce substantial economies in manufacture and generally simplify the work of exchange maintenance.

According to one feature of the invention the discriminating portion and the selector portion of the arrangement are formed as independent units, and the selector portion is made capable of functioning either as a first code selector for use in a register controller system incorporating zone metering or in a multi-exchange system such as for example a satellite exchange system with zone metering and route discrimination under control of a separate discriminating unit accessible in common to a plurality of selector portions. Preferably also the zone metering equipment of this unit is distinct from the route discrimination equipment so that the two functions may be determined after different numbers of digits have been received.

The invention will be better understood from the following description of one method of carrying it into effect, reference being had to the accompanying drawings comprising Figs. 1 to 9 which should be arranged as shown in Fig. 10 which is inserted at the right hand corner of Fig. 3.

Figs. 1, 2 and 3 show the circuits of a selector and an associated hunter switch which are intended to function in two capacities. On the one hand they may be employed as a first code selector and an A digit selector hunter in a register controller system with provision for zone

metering facilities which may be either level controlled or controlled from the register controller. On the other hand the selector and hunter may be used in a manner to be described in conjunction with the sending unit and discriminating unit shown in Figs. 4, 5 and 6, and 7, 8 and 9 respectively to form a discriminating arrangement with control of metering from the discriminating unit. In the latter case the outgoing junctions to the main exchange are connected to the first level of the selector, this level being reserved for this purpose; no separate junction hunter switch is therefore required.

Figs. 4, 5 and 6 show the circuits of a sending unit which is accessible from the selector of Figs. 1, 2 and 3 over the hunter switch and includes a mechanical impulse regenerating device of the type disclosed in J. W. McClew and C. R. Woodland's application No. 79,830, filed 15th May 1936, which is adapted to receive and store trains of impulses. Upon receipt of a signal from the discriminating unit, the received impulse trains are sent out in regenerated form to actuate either the satellite or parent exchange selectors in accordance with the route discrimination determined in the discriminating unit. Facilities are also provided to absorb certain digits in response to signals from the discriminator by arranging to short-circuit the pulsing-out leads until such time as these unwanted digits have been sent out by the impulse regenerator.

Figs. 7, 8 and 9 show the circuits of a discriminating unit which is directly associated with the sending unit and comprises essentially a uniselector which is set by the calling subscriber's dialled impulses in parallel with the impulse regenerator. The uniselector bank contacts are marked between successive impulse trains and according to the particular cross-connection employed it is possible in response to the dialling of one or more routing digits to effect the determination of the appropriate meter fee and of the proper route for the call.

The two-directional switch employed in the selector is assumed to be of the type disclosed in R. N. Saxby's Patent No. 2,028,689, granted 21st January 1936, having a so-called rectangular motion while the unidirectional switches employed are of the well-known reverse drive type.

For the purpose of the description any connections which are alterable to suit the conditions to be met are inserted in chain dotted form, the connections referred to being those

from the CO and DA terminals in the discriminating unit to the CO and DA terminals in the sending unit and also those from the banks of the D switch to various terminals in the discriminating unit.

Considering first the operation of the equipment on a call from a regular subscriber it will be assumed that his line is extended to the selector shown in Figs. 1 to 3 by way of a line finder or other non-numerical switch. Immediately the selector is seized relay L operates over the incoming line loop in series with the iron hydrogen current limiting device BRA and at armature *l1* operates relay A and I in series to earth over resistance YA, (relay D being non-operative in this condition due to rectifier MRE being in a conductive direction) and at armature *l2* operates relay B. A circuit is thereby closed for the lower winding of relay C over armature *b1* and *a2*, while relay BB operates over armature *b2*. Relay BB in operating thereupon at armature *b1* applies guarding potential to the incoming P conductor while relay C in operating at armature *c3* completes a self-interrupted driving circuit for the sending unit hunter switch magnet SUHM from earth which is connected to a common lead *l7* by way of equipment which is arranged to give a delayed alarm in case of failure to release, armatures *k2* and *m4*, wiper H in the home position, armatures *c3* and *kr3*, interrupter contacts *suhm*, magnet SUHM to battery.

Accordingly the switch rotates in search of a disengaged sending unit which is marked by battery potential on the associated P contact. When the test wiper P encounters a free outlet relay K operates quickly over:—earth, resistance YD, armatures *a1* and *m2*, windings of relay K in series, P wiper and P lead to battery over armatures *co6* and resistance YE in parallel with the left-hand winding of relay IA in the idle sending unit. Relay K upon operating at armature *k2* disconnects the magnet driving circuit to arrest the motion of the switch and at armature *k1* extends a guarding and holding potential by way of its low resistance lower winding; at the same time the short circuit is removed from relay KR which now operates from earth over resistance YD, winding of relay KR, contacts *m3*, *c5*, resistance YB to battery. The upper winding of relay K is energised in an opposing direction to its lower winding in order to enable it to release in the case of a dual connection. In the case of a dual connection the two K relays are arranged to operate from the same idle marking battery but the holding flux produced in each, due to the current through their low resistance lower windings will be halved while the opposing flux due to their upper windings will remain the same. In these circumstances both the K relays will release and cause the hunter switches to continue searching. Due to the difference in the speed of any two switches, after a few steps one will reach a free outlet before the other, whereupon the associated K relay will operate to guard the outlet and disconnect the driving circuit. This testing arrangement enables relay K to differentiate accurately between the hold and release currents under single and dual connections respectively.

Relay KR upon operating, at armatures *kr3*, *kr4*, *kr5*, *kr6* and *kr7* switches the control leads through to the sending unit, whereupon earth is extended from armatures *l2* and *kr4* over the PU lead to hold relay IA in the sending unit, this

relay having been initially operated over its left-hand winding in series with relay K. A loop by way of armatures *l_{m2}* and *l_{d4}* in the sending unit is returned over the negative and positive conductors to maintain relay A operated in the selector. Relay IA in operating at armature *l_{a1}* operates relay IB in series with the impulse regenerator receiving magnet MR, the resistance YG serving to prevent false impulses to the magnet MR when all three springs of relay IA are 10 in contact. Relay IB in operating at armature *l_{b1}* completes a locking circuit for itself, at armature *l_{b3}* lights the supervisory lamp ILP from earth which is connected to common lead 20 by way of delayed alarm equipment, at armature *l_{b4}* connects relay TP to the S pulse cam for a purpose to be described later, while at armature *l_{b5}* earth is connected to the common holding lead HL whereupon relay LR is operated. Relay LR in operating at armature *l_{r2}* connects an 20 earthed dial tone transformer over common lead 21 and condenser QB on to the FR lead extending to the selector when the dial tone finds a circuit through condenser QA and the earthed upper winding of relay I, whereupon it is applied to the incoming speaking conductors in a balanced circuit by induction through the windings of this relay. At armature *l_{r4}* the left-hand winding of relay IA is disconnected from the incoming P lead but this relay remains held over 30 the earthed pulse lead PU on its right-hand winding.

It will be noticed that the idle marking battery connected to the P lead initially comprises the left-hand winding of relay IA and resistance YE 35 in parallel and on operation of relay LR consists of resistance YE only; this two-stage arrangement gives better initial operating and subsequent holding or releasing condition for the selector K relay.

The subscriber now dials the first digit and relay L in the selector responds and at armature *l2* repeats the impulses over the PU lead to relay IA in the sending unit. Each time relay IA releases a circuit is completed to energise the impulse regenerator receiving magnet MR as follows:—earth, armatures *l_{b1}*, *l_{a1}* and *co5*, magnet MR to battery while at the same time relay IC is energised in parallel. On each release of relay IA a circuit is also completed to energise 50 the magnet DM of the switch in the discriminating unit as follows:—earth, key contacts KB2, armatures *l_{b5}* and *l_{a2}*, IPU lead, armature *zm2*, magnet DM to battery. Accordingly the digit is mechanically stored in the impulse regenerator 55 in a manner to be described, while the switch D in the discriminating unit is advanced to a position corresponding to the digit dialled. During the impulse train it will be noticed that relay IB is intermittently short-circuited by the resting 60 armature *l_{a1}* but this relay will remain held due to the slugging effect of the short-circuited winding, while relay IC will hold during the impulse train due to its slug. It will be readily understood that neither the magnet MR nor relay IC 65 will either operate or hold in series with relay B and moreover the inductance of the relay IB is such that it has no appreciable effect on the magnet performance.

It should be explained that the mechanical impulse generator hereafter termed regenerator comprises essentially a receiving ratchet wheel X which is rotated step-by-step under control of the receiving magnet MR and which is arranged on one side of a fixed disc Z carrying round its 70 75

periphery a row of 40 pins. The rotation of the receiving disc stores up energy in a clock spring to drive the sending disc Y and thus actuate the impulse springs IMP and send out regenerated impulses of the correct character and rate. Before the reception of the first digit, the armature of a so-called marking magnet is resting on a pin in the disc Z which it has pushed forward to restrain the sending disc Y. During the first digit relay 1C operates and holds during the impulse train and at armature 1c3 energises the marking magnet MM which tilts a lever carried by the receiving disc X out of engagement with the pins. At the end of the digit the receiving disc will have been rotated a number of steps equal to the number of impulses in the train and on release of relay 1C the marking magnet is de-energised and allows the lever carried by the receiving disc X to tilt back towards the disc Z thereby displacing a corresponding pin into the path of the disc Y thus virtually storing the digit dialled. Hence if the successive digits dialled are 5, 4 and 7 pins numbers 5, 9 and 16 from the original resting positions are displaced. It should be noted that the sending disc Y is at present restrained by the pin which was displaced at the end of the previous call. When the receiving disc is first moved off normal, the off normal springs MN close and at the end of the digit when relay 1C releases relay ON operates over contacts MNI and armature 1c1 and locks to the operated off normal contacts at armature on1 and at armature on2 disconnects the dial tone.

Meanwhile the D switch in the discriminating unit Figs. 7, 8 and 9 has also been stepped by the trains of impulses and in a manner to be described more fully later determines whether the call is to be routed locally or by way of an outgoing junction to the parent exchange, this discrimination taking place after the first, second, or third digit.

Assuming first that the call is to be routed through the parent exchange, then after reception of one, two or three digits earth will be applied to the JD lead extending from the discriminating unit to the sending unit whereupon relay JD will be operated over its right-hand winding and at armature jd1 locks to the earthed holding lead HL. Relay JD in operating at armature jd2 operates relay LD and at armature jd3 operates relay IP whilst at armature jd4 it opens the holding loop for relay A in the selector over the outgoing negative and positive conductors. Relay LD in operating at armature ld1 disconnects relay LR and hence during the release time of this relay the outgoing loop to relay A in the selector will be opened, but on release, armature lr3 again extends a loop by way of the impulse springs IMP and armature lm2 to re-operate relay A.

Referring now to the selector circuit, relay A in releasing at armature a2 completes a circuit from earth by way of armatures b1, a2 and c1 to energise the vertical magnet VM in series with the low resistance upper winding of relay C and accordingly the selector wipers are raised to the first level on which are wired the outgoing junctions to the main exchange whereupon the off normal contacts N are mechanically operated and at contacts N1 extend earth from armature c2 to operate relays HB and HA over their middle windings. On re-operation of relay A, the vertical magnet energising circuit is disconnected while relay C now releases after a short interval due to its slug since its preenergising circuit over

its lower winding is disconnected at off normal contacts N2. Relay C in releasing at armature c2 completes an energising circuit for the rotary magnet RM from earth, armatures bb3, m1, db1, hb3, ha3, rotary magnet interrupter contacts rm, off normal contacts N1, armature c2, magnet RM to battery and the wipers will therefore be advanced into engagement with the first set of the contacts in the level selected whereupon the rotary off normal springs NR will be mechanically operated while the magnet interrupter contacts rm will also be opened.

If both the outlets encountered by the P1 and P2 wipers are engaged, that is, they are marked by the presence of earth potential on the test contact, relays HB and HA will be maintained operated on their right-hand windings and the disconnection by the contacts rm of their initial operating circuits over their middle windings is therefore without effect. However the rotary magnet RM which is connected in parallel with these relays releases and when the interrupter contacts again close the magnet is again energised to advance the wipers on to the next set of contacts. This stepping operation continues automatically until either a free outgoing junction to the main exchange is found or alternatively the wipers are advanced to the 11th position.

Assuming now that the wiper P2 is the first to encounter a free outlet, there will be no earth potential to hold relay HA operated when the interrupter contacts rm open and this relay will quickly restore and at armature ha3 open the driving circuit while the selected outlet is immediately guarded from earth, armatures ha4 and hb4 and the P2 wiper. Relay HB will however remain held from the busy marking potential picked up by wiper P1. A circuit is now completed from earth, armature b1, rotary off normal contacts NR2 and armature ha5 to operate relay BA and thereupon at armatures ba2, ba4, ha1, hb1 and hb5 the negative and positive pulsing out leads from the sending unit are switched through to the lower set of negative and positive wipers whereupon the loop extended from the sending unit now operates the A and B relays in the main exchange incoming switch in preparation for the reception of regenerated pulses. Armature ba1 disconnects the right-hand winding of relay HB from the testing wiper P1 and this relay now holds as follows: earth, armatures bb3, m1, db1, hb3 and ha3 to battery over its left hand winding.

If however the P1 wiper is the first to encounter a free outlet, relay HB releases to open the magnet driving circuit at armature hb3 while the outlet selected is immediately guarded over this wiper from earth, armatures hb6, bb6 and m8. Relay BA will be operated as previously described and extends the loop from the sending unit over the upper set of wipers through to the junction.

In case both test wipers encounter free outlets, both test relays HA and HB restore whereupon relay BA is energised as above and relay HA is re-operated on its left-hand winding from earth, armatures bb3, m1, db1 and hb3 and rotary off normal contacts NR1. The pulsing out loop is therefore switched through to the upper set of wipers and it will be seen that priority is always given to the upper set of wipers in these circumstances.

If all the outlets in the level selected prove busy the wipers are rotated to the 11th position where the cam springs S are mechanically operated. Relays HA and HB release since the P1 and P2 wipers encounter no earth potential and relay

BA is thus energized. Relay HA is then re-operated as before and switches the pulsing out loop to the upper set of negative and positive wipers and since they are resting on unwired contacts the stored pulses subsequently transmitted from the sending unit will be sent out into an open circuit and thus do no harm. Cam contacts S2 connect the upper winding of relay I in circuit with the busy tone transformer which is connected to common conductor 16 whereupon busy tone is returned to the subscriber in a balanced circuit to inform him that he must hang up and re-dial.

Returning now to the sending unit, relay LR on releasing at armature *lr*5 completes a circuit to operate relay P from earth, regenerator off normal contacts MN1, fixed disc Z which is in contact with a pin left projecting from a previous call, the reset pin in the disc Y which bears against the former pin, sending magnet interrupter contacts *ms*, armature *lr*5, winding of relay P to battery. Relay P in operating at armature *p*2 energizes the control switch magnet CNM, at armature *p*3 disconnects relay IP, at armature *p*4 prepares an energizing circuit for the regenerator sending magnet MS, and at armature *p*5 completes a locking circuit for itself. The release time of relay IP is arranged to be of the order of 600 milli-seconds which period allows the selector ample time to hunt for a free outlet and on release of this relay the regenerator sending magnet MS is energised whereupon relay P now releases since its holding circuit is disconnected at both the interrupter contacts *cnm* and *ms*, associated with the magnets CNM and MS respectively. Relay P in releasing re-operates relay IP at armature *p*3 in preparation for providing the next interdigital pause while at armatures *p*2 and *p*4 the magnets CNM and MS are de-energised whereupon the CN wipers are advanced to position 2. During the operation of the sending magnet MS the reset pin is moved to restore to its normal position the movable pin in the disc Z against which it has been resting and the sending disc Y is now free and rotates due to the wound clock-spring and operates the impulse springs IMP to send out impulses over the outgoing negative and positive leads, the first train of pulses sent out serving to set the main exchange selector. The sending disc rotates until it encounters the pin displaced at the end of the first dialled digit when relay P will be energised as before and will again open the circuit of relay IP and the sending out of the second digit will be held up until relay IP fully releases. This process is repeated for each digit stored and it will be appreciated that the regenerator is capable of receiving and transmitting impulse trains simultaneously. It will be seen that for this type of call the dialled digits are merely regenerated and retransmitted.

The necessary multi-fee registration is set up in accordance with the digits dialled from the discriminating unit over the metering leads M2, M3 and M4 on to relays 1MA and 1MB and is retransmitted to the selector. For example if relay 1MB only is operated, relay MB in the selector will be operated on its right-hand winding in series with the magnet SUHM over the MB lead and connects up to the double fee metering lead at armature *mb*3 whilst if relay 1MA only is operated relay MA in the selector will be operated in a circuit over earth, resistance YF (Fig. 6), armature *lma*4, FR lead, FR bank and wiper, armature *kr*5, upper winding of relay MA in

series with the right-hand winding of relay M to battery, the YF resistance being such that relay M cannot operate in this circuit: relay MA in operating at armature *ma*2 connects up the triple fee metering lead. If both relays MA and MB are operated the quadruple metering lead will be connected up, whilst if neither is operated the single fee lead is connected up.

After all switches in the train have been set the wanted subscriber, if free, will be signalled in a normal manner by ringing current transmitted from the final selector in the train and when he answers, the current will be reversed over the speaking conductors so that rectifier MRE bridged across relay D in the selector will no longer be in a conductive direction thus allowing this relay to operate. Thereupon at armature *d*1 it connects up the left-hand winding of relay DA to the S pulse cam of the meter delay set and at armature *d*2 prepares a locking circuit for this relay over its middle winding. The delay set comprises so-called S and Z pulse cams arranged to supply battery pulses with a definite time relation to two corresponding leads. On transmission of the next S pulse, relay DA will be operated and at armature *da*5 prepares a circuit for relay DB which is operated after the appropriate time interval from the Z pulse in series with the right-hand winding of relay DA. Relay DA remains locked over its middle winding in series with resistance YC until relay DB operates on the Z pulse when both the initial energising circuit and the locking circuit for relay DA are opened but this relay remains held on its right-hand winding in series with the lower winding of relay DB for the duration of the Z pulse. During the application of the Z pulse relay RG is connected by way of armatures *da*2, *da*4 and the armatures of relays MA and MB to the selected metering lead and in accordance with the setting of these two latter relays, relay RG will be operated a predetermined number of times and at armature *rg*1 will repeat these pulses over the incoming P conductor in the form of booster battery pulses to actuate the subscriber's meter. At the end of the Z pulse, relay DA restores to prevent any further operation of the metering relay RG while relay DB remains operated from earth via armatures *bb*3 and *m*1 on its upper winding in series with the left-hand winding of either relay HA or relay HB since the upper winding is no longer short-circuited at armature *db*1.

Assuming now that the call is to be routed over local switches the equipment is arranged to absorb any unwanted digits. If, for example, it is arranged to absorb the first two digits, earth will be extended over the LD lead from the discriminating unit at the end of the third dialled digit, thus operating relay LD in the sending unit. This relay in operating at armature *ld*1 disconnects relay LR and also locks via this armature to the earthed holding lead. During the release time of relay LR no preliminary impulse is given to the A relay of the selector since relay JD is normal and maintains a loop across the outgoing negative and positive contacts by way of armatures *lm*2 and *jd*4. On release of relay LR the regenerator is started up and sends out the two unwanted digits but these are nullified by the resting armatures *lm*2 and *jd*4 across the impulse springs IMP while since relay IP is unoperated no interdigital pause is given between the absorbed digits. It will be remembered that the CN switch is stepped forward one contact before the sending out of each digit and thus during the sending of the first

digit, wiper CN3 will be connected to tag DA2, during the second digit to tag DA3 and so on. During the sending out of the second unwanted digit wiper CN3 will encounter earth on terminal DA3 which earth is extended from the discriminating unit in a manner to be later described and this earth energises relay IP. When relay P subsequently operates in a normal manner after the sending of this last absorbed digit, relay JD will be operated over its left-hand winding from earth over armatures ip_1 and ip_6 and at armature jd_1 locks to the holding lead, at armature jd_3 disconnects the operating circuit of relay IP and at armature jd_4 removes the short circuit from across the regenerator impulse springs IMP. On release of relay IP the sending out is re-commenced and from this point it takes place in the manner described for a junction call except that the first selector is stepped to some level other than level one and therefore the main exchange equipment is not used.

The general operation of the apparatus having been dealt with, the method of discrimination will now be described in more detail, reference being had to the discriminating unit. The meter and route discrimination arrangements provided are independent since it is possible that the junction discrimination might have to take place after the first digit whereas the appropriate meter fee might not be known until after the third digit and clearly meter discrimination cannot be effected until after the route has been determined.

In order to cater for complex numbering schemes it is necessary for route discrimination to take place after the first, second or third dialled digit and therefore if discrimination takes place after the second digit the first will have to be absorbed whilst if discrimination takes place after the third digit the first two digits will have to be absorbed. It will be assumed by way of example that an area has the following numbering scheme: routed to main exchange over level 1 (2000—6999, 8000—9999); routed to manual board over level 0 (0); routed to adjacent automatic exchange over level 3 (73000 to 73999); routed locally over levels 5—8 (71500—71899); routed locally over level 2 (72000—72599).

Consider first the case in which the main exchange number 8456 is dialled. In addition to the digit being stored on the regenerator in the manner previously described the first digit dialled will step the switch D to contact 9 (the home position being contact 1) and at the end of this digit relay IC in the sending unit releases and at armature ic_2 extends the earthed holding lead over the C lead to wiper D7. Since it is required to route the call through to the parent exchange, contact 9 on the D7 bank will be connected to tag m and thence by way of armature da_5 and a cross connection between tags k and a on to the JD lead. Thus relay JD in the sending unit will be operated at the end of the first digit and will cause the digit stored in the regenerator to be sent out in the manner hereinbefore described. The remaining digits in the number dialled further step the switch D for the purpose of determining the meter fee in the manner to be described later.

Assume now that the number 71822 is dialled, this being a local exchange number requiring the absorption of the first two digits 71. It will be remembered that on this type of call relay LD is operated from the discriminating unit at the end of the third dialled digit while it is necessary to

earth terminal DA3 in the sending unit. The terminals DA1 to DA3 in the sending unit are cross-connected to terminals DA1 to DA3 respectively in the discriminating unit to enable the necessary absorption to take place. In this example it will be necessary to operate relays $1DA$ and $1DB$ before operating relay LD in order to prevent the earth from the holding lead HL being extended on to terminals DA1 and DA2. On reception of the first digit 7, wiper D7 will be stepped to contact 8 which is strapped to terminal J thereby operating relay $1DA$, which in operating at armature $1da_1$ locks to the earthed lead HL while at armature $1da_4$ it disconnects the earth from the terminal DA1. The second digit 1 steps switch D further to contact 9 which is strapped to terminal m thereby operating relay $1DB$ which locks and removes the earth from terminal DA2 at armature $1db_6$. On dialling the third digit 8 the switch is advanced to contact 17 which is strapped to terminal g whereupon earth will be extended at the end of this digit on to the LD lead by way of the cross-connection and armature $1db_2$. Relay LD in operating initiates the sending out of the regenerator as previously described for a local call. The following digits 22 further step the D switch in case the meter fee cannot be determined until the 4th or 5th digit.

It will be seen therefore on consideration that tags $a-m$ and the associated contact combinations of relays $1DA$ and $1DB$ enable any numbering scheme to be catered for with discrimination on first, second or third digits. By the use of additional relays the discrimination may be deferred until the 4th and 5th digits, in which case terminals DA4 and DA5 in the sending unit would be brought into use. Since only one bank of the D switch, that is the D7 bank, is used to provide the route discrimination, it is necessary to provide the above arrangement to preclude any possibility of a call being incorrectly routed, where for example, the D switch is stepped to the same position in response to either main exchange or local or other routing digits. For example, on a junction call, digit 8 may be dialled as a first digit, at the end of which earth is extended over the D7 wiper in position 9 by way of tags m , k and a on to the JD lead whereupon relay JD will be operated; at the same time the dialling of the first two digits 71 of a local exchange number would also step the D switch to contact 9. In order to prevent the operation of relay JD in this case which would misroute the call, relay $1DA$ is operated at the end of the first digit in the manner previously described, and at armature $1da_5$ thereupon changes over the link between contact 9 and the JD lead to relay $1DB$ in preparation for the second digit 1.

The switch D is also used to determine the appropriate meter fee and this may not be possible until as many as five routing digits have been dialled according to the complexity of the network. The D switch is further used for the important function of barring access to various routes under certain conditions. Assuming now that the dialling of two digits 73 will route the call into a particular meter fee zone, the switch D will be stepped to position 8 after the first digit and during the inter-digital pause earth will be extended over the C lead by way of resting armatures sd_2 , sc_2 , sb_2 and sa_2 and thence via a strapping connection from contact 8 to terminal SA. Relay SA is thereupon operated and locks to the HL lead and at armature sa_2 switches over the C lead on to the D2 wiper in preparation for the

next digit. On reception of the next digit the switch is further stepped on to contact 11 while at the end of this digit earth will be extended by way of a strapping from contact 11 on the D2 bank to the appropriate meter fee terminal 1-4 or 1 (CCB barred), the use of the latter terminal being explained later. Should for example a double meter fee be required the connection will be taken from contact 11 on the D2 bank to terminal 2 and thence by way of armature rs3 (relay RS being normally operated on a call from a regular subscriber) on to the M2 lead and thence to the sending unit whereupon relay 1MB is operated and this relay in turn operates relay MB 15 in the first selector which connects up the double fee metering lead. Relay 1MA or 1MB in operating extends an earth over the ZM lead into the discriminating unit whereupon relay ZM is operated over its right-hand winding and at 20 armature zm3 locks to the earthed holding lead HL. Armature zm1 extends an earth by way of its left-hand low resistance winding to self-drive the D switch to the home position, since the remaining digits to be dialled need not actuate this switch. Furthermore on the subsequent release of the common equipment when all digits have been dialled it can be made more quickly available for further common use since there is no necessity to wait for the D switch to home. In 25 the case of single fee calls relays 1MA and 1MB would not be operated, relay ZM being operated direct from the meter fee terminal 1.

Relays SA to SD serve in effect to increase the number of individual bank contacts over 35 which the switch travels by switching the C lead as required and thus in conjunction with the banks D2-D6 the meter discrimination may be deferred until up to five digits have been dialled.

Relays CA, CB and CC provide cut-off conditions for varying numbering schemes in order 40 that the common equipment can be released immediately a sufficient number of digits have been dialled. In the area assumed, for the five digit numbers, relays CA to CC will be unaffected and 45 an earth would thus be extended over resting armatures cc6, cb6 and ca6 on to terminal CO1 and thence via a cross connection to terminal co5 in the sending unit. Since the switch CN in the sending unit is advanced one step before each 50 digit is sent out, wiper CN4 will be advanced to position 6 thereby making connection with terminal CO5 just prior to transmission of the 5th digit. At the end of this digit since there are no 55 more digits stored in the regenerator the transmitting disc Y will catch up with the receiving disc X whereupon the off normal springs MN will be opened. There will thus be no circuit to operate relay P in the normal manner but relay ON will release and at armature on6 it opens the 60 holding circuit of relay IP. This relay releases after a short interval when relay CO will be operated from the earth encountered by the wiper CN4 and at armature co2 extends an earth on to the common conductor 18 extending to delayed 65 alarm equipment which gives an alarm in case the apparatus fails to restore to normal within a predetermined time, at armature co3 connects up interrupted earth over common lead 19 to the supervisory lamp 1LP, at armatures co4 70 and co5 disconnects any circuits to the regenerator marking and receiving magnets while at armature co6 the idle marking battery is disconnected from the incoming P lead thus releasing relay K in the selector. Relay K in releasing 75 thereupon at armature k1 short circuits relay KR

causing it to release and at armature kr4, kr5 to disconnect the control leads through to the sending unit and at armatures kr6 and kr7 to connect the incoming speaking leads through to the negative and positive wipers. At armature kr8 5 a homing circuit is completed for sending unit hunter switch from earth on common lead 17. Relay 1A in the sending unit now releases and in turn releases relay 1B which removes earth from the holding lead HL thus releasing all 10 relays held thereunto whilst the switch CN is homed to one of its two home positions. Relay CO is maintained operated during the homing of this switch to guard the common equipment until all the apparatus therein has restored to 15 normal.

For four digit numbers the meter discrimination is not wired direct from one of the banks D2 to D6 to the required unit tag but via a changeover contact of relay CA so that this relay 20 operates before passing the signal to relays 1MA, 1MB or ZM. In this case therefore CO tag 2 is wired to terminal 4 associated with the CN4 bank to give a cut-off after four digits have been sent. Relays CB and CC are used for example to cater 25 for single digit and six digit numbers respectively while if more than four different kinds of numbers exist in the same network additional relays are provided. Sufficient CO terminals are connected to the CN4 bank to cater for a cut-off 30 after the sending out of up to nine digits.

On calls from regular subscribers, as soon as relay LR is operated in the sending unit, relay RS is operated on its right-hand winding over the RS lead, armatures lr3, jd4 and lm2, negative lead, winding of relay A in the selector to battery. On coin box calls however an earth is extended from the line finder over the D lead to the selector and serves to shunt relay RS and prevent its operation. It will therefore be seen 40 that the meter fee terminals 1 (CCB barred), 2, 3 and 4 are extended to the spare code lead SC thus operating relay 1M at some point of the call. This relay in operating, locks at armature lm1 to the holding lead, disconnects the loop over the 45 outgoing negative and positive conductors at armature lm2, prepares a circuit for earthing the forced release lead FR at armature lm3 and earths the ZM lead to home the D switch at armature lm4. The disconnection of the loop will 50 prevent any further impulses sent out from the regenerator from being effective whilst if a junction call is being set up the distant equipment will be released. After all digits have been sent out from the regenerator relay ON will be released and on release of relay IP after its slow release period an earth will be extended on to the FR lead by way of armatures ip1, on4 and lm3. This delay period ensures a guarding overlap on 55 junction calls, since on earthing the FR lead the junction is freed at the local outgoing end. Relay M in the selector is now operated on its right-hand winding and locks up over its left-hand winding at armature m1 and also disconnects the holding circuit of relay DB and either 60 relay HA or relay HB whichever is operated at the same armature, releases relay KR at armature m3, opens the homing circuit of the hunter switch SUH at armature m4, earths common lead 12 extending to supervisory equipment at 65 armature m5, connects flicker earth over common lead 10 at armature m6 to the lamp LP which is connected to battery by way of delayed alarm equipment connected to common conductor 70 m1 so that in case relay M is maintained operated 75

for longer than a predetermined period an alarm will be given while the lamp flashing will indicate the switch involved to the maintenance officer. Armature *m1* connects up the NU tone transformer over common lead *l3* to the upper winding of relay *I* whence the tone is returned to the calling subscriber in a balanced circuit while armature *m8* prevents an earth being extended on to the *P* lead when relay *HB* releases.

Either relay *HA* or *HB* in releasing, frees either the junction or the local train of switches while relay *KR* in releasing at armature *kr4* removes the earth from the *PU* lead thus releasing relay *IA* and freeing the common equipment. During the release of this equipment relay *CO* will be operated and at armature *co6* releases relay *K* in the selector which removes the guard earth from the *P* wiper at armature *k1*. Thus by taking the meter fee cross-connection in the discriminating unit to terminals 1 (CCB barred) 2, 3 and 4 coin box subscribers can be prevented from setting up certain single fee and all multi-fee calls without the intervention of an operator. Spare positions on the banks *D2*—*D6* are also connected to the *SC* lead and hence if the subscriber dials a spare code he will receive NU tone.

Should the calling subscriber receive dial tone and then wait longer than a predetermined period before dialling, relay *TP* in the sending unit will function on the *S* pulse and at armature *tp2* connects the *Z* pulse lead to relay *IM* which operates subsequently on the *Z* pulse. Relay *M* in the selector is then operated immediately over the *FR* lead from earth by way of armatures *ip1* and *on4* whereupon the common equipment is freed but no tone is returned to the subscriber since relay *C* has not yet been operated. Should the subscriber now dial relay *A* will respond in series with relays *D* and *I* when the selector will be raised vertically but cannot hunt in a rotary direction since the rotary magnet energising circuit is disconnected at armature *m1*. On release of relay *C* at the end of the first digit dialled the subscriber will receive NU tone in the normal manner whilst no more impulses can be delivered to the vertical magnet since relay *C* cannot be re-operated.

If however the subscriber dials one or two digits and then fails to dial the remainder, relay *IM* will be operated as above and in case the regenerator has not started sending out due to the fact that the *D* switch in the discriminator has not received sufficient digits to determine the type of call the *FR* lead will be earthed over resting armature *ld2* and armature *lm3*.

The sending unit is provided with a so-called meter and time pulse disconnection key *KD* which allows a maintenance officer to effect a continued routine on the unit without any operation of the traffic recorder and without the time pulse mechanism coming into effect. A busying key *KB* is also provided which is operated when it is desired to "busy-out" the unit; on operation the supervisory lamp *LP* is lit over contacts *KB3*, the idle marking battery is disconnected from the incoming *P* conductor contacts *KB4*, the earth for the common lead is disconnected at contacts *KB2* and the operating earth for relay *IB* is disconnected at contacts *KB1*.

If any switch in either the sending or discriminating unit is moved off normal by hand for example, relay *CO* will be operated to guard the equipment during the homing of the switch.

On dialling the digit 0 the subscriber is routed to the manual board at the main exchange over a special set of junctions from the 0 level of the selector. Should he require a trunk call which cannot be completed on demand the operator 5 may hold the connection by the application of battery to the positive lead and the subscriber may then restore his receiver. Relay *L* in the selector will then release but the battery connection will be extended over the positive lead, lower 10 winding of relay *I*, armatures *l1*, *da4* and *da3*, rectifiers *MRA* and *MRB* in a conductive direction and armatures *db4* and *dl* to earth. Hence relay *I* is held operated and at armature *il* holds relay *B* and thus prevents release of the connection. 15 Relay *RG* is non-operative in this condition as it is shunted by the rectifiers. When subsequently the operator desires to re-ring the calling subscriber in order to complete the call however, she operates her ring key which applies 20 booster battery to the positive lead. This will find a circuit as before by way of the winding of relay *I* to earth but in this case rectifiers *MRA* and *MRB* will be non-conductive while rectifiers *MRC* and *MRD* will become conductive and 25 relay *RG* will therefore be operated. Armatures *rg2* and *rg3* thereupon apply continuous ringing current over common leads *l4* and *l5* and armatures *db6* and *db7* to the incoming speaking conductors and thus re-ring the calling subscriber. 30 Armatures *db6* and *db7* serve to prevent ringing current being applied to the line when relay *RG* is being used as a meter pulse relay.

On any connection, when the calling party restores his receiver at the conclusion of conversation, relay *L* releases and opens the circuit of relay *B*. After a short period relay *B* releases and opens the circuit of relay *BA* which releases after a further short period. Armature *ba3* thereupon removes earth from the incoming *P* conductor 40 and also releases relay *BB* whereupon armature *bb1* reconnects earth to the *P* lead by way of the operated off normal contacts *M3*. Relay *BB* also at armature *bb3* releases relay *DB* and either relay *HA* or relay *HB*, these relays being previously held in series. In case relay *HA* had been operated thus indicating that the upper set of wipers had been in use, the guard earth which was applied by way of armatures *hb6*, *bb6* and *m8* to the *P1* wiper is now disconnected at armature *bb6* while in case relay *MB* had been operated to connect up the lower set of wipers, the guard earth normally applied by way of armatures *ha4* and *hb4* to the *P2* wiper will now be disconnected at armature *hb4*. It will be seen therefore that 50 a double guard period represented by the sum of the release times of relays *B* and *BA* is provided on both the outgoing *P* leads in order to adequately cover the release of the distant exchange selectors and prevent the seizure of the junction before they have completely released. On release of relay *BB* a self-interrupted driving circuit is completed for the magnet *RM* from the earthed lead *l7* and accordingly the wipers are rotated clear of the banks after which they fall and rotate under the banks under spring tension back to their normal positions where the off normal contacts *N1* open and disconnect the homing circuit. Preferably the rotary magnet is mechanically prevented from opening its interrupter contacts during the release movement so that there is no tendency for it to chatter.

To facilitate testing, the test jack springs *T* are provided, their use being readily ascertained from the drawings. Furthermore each magnet is 75

provided with a spark quench arrangement which preferably consists of a resistance and condenser in series.

We claim:

5. 1. In a switching control system, control equipment, means for seizing said control equipment and for transmitting thereto trains of impulses, said control equipment effective to receive and regenerate all of said trains of impulses and to retransmit all or part of said regenerated trains of impulses in accordance with a determination made from a portion of the received trains of impulses, means normally effective during the regeneration of said trains of impulses to insert 10 an interdigital pause between successive regenerated trains of impulses, and means controlling said last means to substantially prevent the insertion of an interdigital pause between successive trains of impulses which are regenerated but 15 not re-transmitted.

2. In a telephone or like system wherein connections are extended over automatic switches, a controller for operating said switches, means for seizing said controller and transmitting thereto 20 a code of impulses to direct the extension of a connection, a first register in said controller operated by said impulses to register the whole of said code, a second register in said controller also operated by said impulses to register the whole of 25 said code, means in said controller controlled by said first register for determining the path over which said connection is to be extended, means for operating the switches in accordance with said determination to extend the connection over 30 said path, and means in said controller controlled by said second register independently of said first register and of the connection extended under control of said first register to assess an arbitrary 35 value to said extended connection, said value depending upon part of the code registered by said second register.

3. In a telephone or like system wherein connections are extended over automatic switches, a register controller for operating said switches, 40 means for seizing said register controller and for transmitting thereto a plurality of digits to direct the extension of a connection, means in said register controller for registering at least part of said digits transmitted to said register controller 45 and for determining from said part thereof which of the digits transmitted to said register controller shall be retransmitted, other means in said register controller for registering all of said digits transmitted to said register controller and 50 for retransmitting certain thereof in accordance with said determination made by said last means, thereby to operate said switches to extend said connection, and still other means in said register controller for registering at least part of said digits transmitted to said register controller and, 55 in accordance with said part, assessing an arbitrary value to the connection extended by said switches under control of said retransmitted digits.

4. In a telephone or like system wherein connections are extended over automatic switches, a register controller for operating said switches, means for seizing said register controller and for transmitting thereto a plurality of trains of 60 impulses to direct the extension of a connection, means in said register controller for receiving said trains of impulses and for subsequently retransmitting certain thereof to operate said switches to extend the connection, a discriminating 65 switch in said register controller having a 70

plurality of wipers operated by all of said received trains of impulses, a circuit completed over one wiper of said discriminating switch when a certain number of said trains of impulses have been received, means controlled over said 5 circuit for determining which of the received trains of impulses shall be retransmitted and for controlling said last means to retransmit only those trains of impulses, another circuit completed over a different wiper of said discriminating switch when a certain number of said trains of impulses have been received, and means controlled over said last circuit for assessing an arbitrary 10 value to said connection extended by said automatic switches under control of said retransmitted trains of impulses, said value depending upon certain of the received trains of impulses.

5. In a telephone or like system wherein connections are extended over automatic switches, 20 a register controller for operating said switches, means for seizing said register controller and for transmitting thereto a plurality of trains of impulses to direct the extension of a connection, means in said register controller for receiving 25 and subsequently regenerating all of said trains of impulses, other means in said register controller for receiving said trains of impulses and for determining from certain thereof which, if any, of the regenerated trains of impulses shall be 30 absorbed in said register controller, means for counting the regenerated trains of impulses, and means controlled conjointly by said last two means for at times preventing one or more of the regenerated trains of impulses from being transmitted to operate said switches.

6. In a telephone system or the like wherein connections are extended over automatic switches, control equipment, means for seizing said equipment and transmitting thereto trains of impulses each having a certain digital value, means in said equipment responsive to said trains of impulses and effective subsequently to regenerate all thereof, separate means in said equipment also responsive to said trains of impulses and effective, upon said regeneration thereof, to at times suppress certain of the regenerated trains of impulses depending upon the digital values of one or more of the received trains of impulses, and means for transmitting 50 only the unsuppressed regenerated trains of impulses to operate the automatic switches to extend a connection.

7. In a system as claimed in claim 6, means controlled by said separate means for at times initiating said regeneration responsive to the receipt of a certain number of trains of impulses and at other times initiating said regeneration responsive to the receipt of a different number of trains of impulses depending upon the digital 60 values of one or more of the trains of impulses received by said separate means.

8. In a system as claimed in claim 6, means controlled by said separate means for at times, in dependence upon the digital value of one of the trains of impulses received thereby, originating an impulse and transmitting same to operate one of the automatic switches before said transmission of the unsuppressed regenerated trains of impulses.

9. In a system as claimed in claim 6, means normally operated to separate successive trains of said regenerated impulses by an interdigital pause of predetermined duration, and means controlling said last means to materially de- 70 75

crease the length of the pause between successive trains of said regenerated impulses if said regenerated trains are to be suppressed.

- 5 10. In a telephone or like system, automatic switches, means for seizing one of said switches and transmitting signals thereto corresponding to the digits of a called station number, common control equipment, means for associating said equipment with a switch when seized, means 10 in said equipment for registering the signals for

each received digit, separate means in the equipment also operated responsive to the received signals and effective in accordance therewith to at times suppress certain of the signals registered by said registering means, and means controlled by said registering means to retransmit only the registered signals not suppressed by said last means.

REGINALD TAYLOR.
GEORGE THOMAS BAKER. 10
